UNITED STATES PATENT OFFICE.

CHARLES G. WILKS, OF COTTER, ARKANSAS.

NUT-LOCK.

1,197,701.

Specification of Letters Patent. Patented Sept. 12, 1916.

Application filed August 31, 1915. Serial No. 48,834.

To all whom it may concern:

Be it known that I, CHARLES G. WILKS, a citizen of the United States, residing at Cotter, in the county of Baxter and State of Arkansas, have invented certain new and useful Improvements in Nut-Locks; and I do hereby declare the following to be a full, clear, and exact description of the invention, such as will enable others skilled in the art 10 to which it appertains to make and use the same.

The primary object of this invention is to admit of a nut being conveniently, expeditiously and securely locked to a bolt. 15 A further object of the invention is to provide a specially constructed nut and bolt and locking means for carrying out the above object, which can be manufactured cheaply, will be durable, and efficient in 20 operation.

Other objects will appear and be better understood from that embodiment of my invention of which the following is a specification, reference being had to the accompanying drawings forming a part thereof, in which:

Figure 1 is a top plan view of the nut lock constructed in accordance with my invention and showing the nut in section so as to expose the locking means. Fig. 2 is a front elevation of the nut removed from the bolt. Fig. 3 is a sectional side elevation, taken on the line 2—2 of Fig. 1. Fig. 4 is a perspective view of the locking key.

Referring to the drawings, the numeral 1 designates a bolt having at one end a head 2 and having its opposite end threaded, as at 3. The threaded end of the bolt is terminally provided with a transversely extending slot 4, which opens into the said terminal of the bolt and into opposite sides of the bolt, and has one end communicating with a longitudinal groove 5 formed in the side of the bolt. The slot 4 is of a depth approximately twice that of the groove 5 and the said slot and groove are rectangular in cross section.

Adjustably mounted on the bolt 1 is a nut 6. The walls of the bore of the nut 6, are, 50 as shown in Fig. 2, provided at diametrically opposite points with grooves 7, the said grooves being, as shown in Fig. 2, rectangular in cross section and one of the grooves is

adapted to register, when the nut is in adjusted position, with the longitudinally extending groove 5 in the bolt. 55

Associated with the nut and bolt is a locking key 8. This locking key is L-shaped in configuration and when in position has the longer arm 9 located within the groove 5 in the bolt, and in the adjacent registering groove in the nut, and the shorter arm of the key is positioned within the transverse groove 4 in the bolt. The longer arm of the key is of a thickness equal, approximately, 60 to the combined depth of the registering groove in which it is positioned, so that the said arm will engage the walls of the respective registering grooves, so as to prevent turning of the nut when the key is in locking position. The shorter arm 10 of the key is of a thickness substantially half the depth of the slot 4, as shown in Figs. 1 and 3, and the walls of the slot are provided, at 65 points in advance of the shorter arm, with opposed and alined openings 11. When the nut and key are in position on the bolt a cotter pin 12 is inserted through the alined openings 11 and when so positioned the terminals of the companion portions of the 70 pin 12, are deflected in opposite directions, as shown in Fig. 1, whereby the key 8 will be held from longitudinal movement on the bolt. 75

By referring to Figs. 1 and 3 of the drawings, it will be seen that when the key and cotter pin are in operative positions, the said pin and the shorter arm 10 of the key will lie wholly within the plane of the adjacent end of the bolt, so that there will be 80 no projection extending beyond the end of the bolt to come in contact with the object or to become broken.

Having thus described my invention what I claim as new, is:

In a nut lock, the combination of a bolt having a longitudinally extending groove in one side thereof, and a transversely extending slot in one end thereof opening into the said end and opposite sides of the bolt and 90 having a depth exceeding the depth of the groove, and having one end communicating with the groove, the walls of the slot having opposed and alined openings therein, a nut adjustably mounted on the bolt and having a groove therein adapted to register with 100

the groove in the bolt, an L-shaped key having the long arm thereof extending into the registering grooves and having its shorter arm positioned within the slot and rear of the openings and being of a thickness considerably less than the thickness of the longer arm, and a pin extending through the said aligned openings in the walls of the slot and located wholly within the plane of the

adjacent end of the bolt and adapted to prevent longitudinal movement of the key.

In testimony whereof I affix my signature in presence of two witnesses.

CHARLES G. WILKS.
